UNITED STATES PATENT OFFICE

ROBERT L. DENNISON, OF KANSAS CITY, MISSOURI

BOILER FEED-WATER APPARATUS

Application filed January 10, 1927. Serial No. 160,270.

This invention relates to water feeding means for steam boilers.

An important object of the invention is to utilize the boiler pressure for equalizing the pressure above and below bodies of water to be fed to the boiler whereby the water may be fed into the bottom of the boiler.

A further object is to provide water feeding means of the type referred to wherein the height of a column of water and a floating piston is utilized for feeding the water to the boiler, the steam pressure in the boiler being utilized for equalizing the pressure above and below the water.

15 A further object is to provide a cylinder into which successive charges of water are adapted to flow, and which charges are adapted to be supplied to the boiler after the cylinder is successively filled.

20 A further object is to provide a pair of cylinders each provided with a floating piston, one of the pistons being movable upwardly under the influence of water pressure to fill the cylinder while the other piston is movable downwardly to combine with the weight of the water in the cylinder to feed the water to the boiler.

A further object is to provide automatic means for alternately connecting the upper ends of the cylinders to the boiler to derive steam pressure therefrom, the cylinder disconnected from the boiler being automatically connected to a source of water supply.

25 A further object is to provide a plurality of water feeding cylinders of the type referred to provided with means for taking care of the alternate expansion and contraction of each cylinder as it is filled with steam and water.

30 A further object is to provide a pair of feed cylinders of the type referred to rigidly connected at their upper ends by suitable heads enclosing valve mechanisms for alternately connecting the upper ends of the cylinders to the boiler to derive steam therefrom.

A further object is to provide an apparatus of the character just referred to wherein the lower ends of the cylinders are free from rigid connection with each other whereby

they are freely adapted to expand vertically as they are alternately filled with steam and water.

Other objects and advantages of the invention will become apparent during the course 55 of the following description.

In the drawings I have shown one embodiment of the invention. In this showing:

Figure 1 is a side elevation,

Figure 2 is a central vertical sectional view 60 through one of the cylinders,

Figure 3 is a detail perspective of one of the shiftable valves,

Figure 4 is a view similar to Figure 2 taken on a plane passing through the axes of both 65 cylinders,

Figure 5 is a detail section on line 5—5 of Figure 2, and,

Figure 6 is a similar view on line 6—6 of 70 Figure 2.

Referring to the drawings the numeral 10 designates a steam boiler of the usual construction having a feed water inlet pipe 11 controlled by a check valve 12. The boiler also is provided with a dome 13 and the usual 75 water gauges 14. A steam pipe 15 is connected at one end to the dome 13, as shown in Figure 1, for a purpose to be described.

Referring to Figures 1, 2 and 4, the numeral 16 designates a pair of preferably vertical parallel cylinders arranged somewhat above the level of the boiler for a purpose to be described. Each of the cylinders is provided at its lower end with a tapered head 17 connected with the pipe 11 through the check valve 12, by outlet pipes 18 through which water is adapted to be supplied to the boiler.

The upper ends of the cylinders are closed and connected to each other by a head indicated as a whole by the numeral 19. This head is provided with a cylinder 20 in which a slide valve 21 is mounted to reciprocate. As shown in Figure 6, the end of the pipe 15 communicates with the cylinder 20 substantially centrally thereof. The slide valve 21 is provided substantially centrally thereof with an annular depression 22 forming a steam passage which is in constant communication with the pipe 15. The depression 22 also is in constant communication with a rela- 100

tively small steam passage 23 formed in the head 19. Adjacent its ends, the valve 21 is provided with annular depressions 24 which are adapted to alternately communicate with exhaust pipes 25 which are open to the atmosphere.

As shown in Figure 6, the head 19 is provided with a pair of intake ports 26 which extend from the interior of the valve cylinder 20 to the interior of the pumping cylinders 16. These ports are adapted to alternately supply the cylinders 16 with steam as the slide valve travels to opposite ends of the valve cylinder 20, in the manner to be described. The admission of steam into the pumping cylinders through the intake ports is adapted to permit downward movement of pistons 27 mounted to reciprocate in the cylinders 16. These pistons are relatively heavy whereby the weights thereof will assist their downward movement, and each is provided with suitable packing rings 28. Each of the pistons 27 is further provided with an upwardly extending axial pin 29 for a purpose to be described. It will be apparent that the pistons 27 are wholly free from any actuating means and move freely within the cylinder. The head 19 is further provided with a relatively small control valve cylinder 30 in which is mounted a control valve 31, as clearly shown in Figure 4. Referring to Figures 3 and 4, it will be seen that the valve 31 is provided with a pair of spaced annular grooves 32, and between these grooves and the ends of the valve the latter is provided with slots 33 extending therethrough. Beneath the valve 31, the head 19 is provided with slots 34 corresponding substantially in arrangement with the slots 33, and bell crank levers 35 are pivotally mounted in the slots 34, as indicated at 36. As clearly shown in Figure 4, one end of each of the bell crank levers is mounted in one of the slots 33 while the opposite end of each lever is adapted to be engaged by one of the pins 29 as each piston 27 approaches its upper limit of movement. Each end of the valve 31 is provided with an axially extending pin 37 which extends through a stuffing box 38 carried by each end of the head 19. These pins are adapted to permit manual operation of the valve 37.

As shown in Figure 2 the axis of the valve 31 is arranged in the plane of the axes of the cylinders 16, while the slide valve cylinder 20 is offset laterally therefrom. The head 19 is provided with a pair of exhaust ports 39 which communicate at their lower ends with the cylinders 16 and at their upper ends alternately with the grooves 24. Each port 39 also is provided with a branch 39' which extends transversely whereby their lower ends communicate with the interior of the control valve cylinder 30. The head 19 also is provided with small ports 40 which com-

municate at their upper ends with opposite ends of the slide valve cylinder 20 and at their lower ends with the interior of the control valve cylinder at a point slightly spaced from the openings at the lower ends of the ports 39'. The head 19 is further provided with a port 41 which communicates at its central portion with the steam port 23. Opposite ends of the port 41 communicate with the interior of the control valve cylinder as indicated in Figure 5, the ends of this port being adapted to alternately communicate with the grooves 32.

Means is provided for introducing water into the lower portions of the cylinder 16 at a substantially low pressure. Referring to Figure 2, it will be noted that each lower cylinder head 17 is provided with a socket 42 which communicates with the interior of the cylinder head through a passage 43. A pipe 44 is provided with a ball head 45 adapted to be received in the socket 42, and a cap 45' is threaded in the socket. This cap is provided with an interior surface 46 which forms a continuation of the surface of the socket 42. Each pipe 44 is provided with a check valve 47 which opens inwardly to admit water into the interior of the cylinders 16. The outer ends of the pipes 44 are connected by a transverse pipe 48 which in turn is connected by a T-joint 49 with a water supply pipe 50. The latter pipe is provided with a globe or similar valve 51 for controlling the passage of the water. The pipe 50 may be connected to a suitable pump 52 which in turn is connected to a source of water supply through a pipe 53.

The operation of the apparatus is as follows:

It will be obvious that when the device is in normal operation, the valve 51 will be open to permit the flow of water into the cylinders. In the position of the parts of the pumping apparatus as illustrated in Figure 4, the right hand piston 27 has just reached the upper limit of its stroke, while the other piston has reached its lower limit while pumping water into the boiler through its corresponding pipe 18 which communicates with the cylinder through the lower cylinder head 17. When the right hand piston approaches its upper limit of movement, the pin 29 contacts with the corresponding bell crank lever 35 moving the free end thereof upwardly to shift the control valve 31 to the right, to the position indicated in Figure 4. When this position is reached, steam will be exhausted from the right end of the slide valve cylinder to the port 40, the latter communicating with the port 39 through the valve groove 32 and port 39'. It will be understood that at this time, the slide valve 21 is at the opposite end of the cylinder 20 from the position shown in Figure 6. The exhaust port 39, previously referred to, will

therefore communicate with the atmosphere through valve groove 24 and exhaust pipe 25. The groove 32 at the right end of the valve 31 will be cut off from communication with the corresponding end of the port 41, while similarly the left hand exhaust port 39 will be cut off from communication with the groove 32 at the left hand end of the valve 31. In this position of the parts, the left hand end of the port 41 will communicate with the groove 32 last referred to, while this groove also will communicate with the lower end of the port 40 at the left side of the apparatus. Thus steam will flow into the space surrounding the groove 22, thence through port 23, the groove 32 at the left hand end of the valve 31, and thence upwardly into the left end of the cylinder 20 through port 40. The steam pressure admitted into the cylinder 20 in the manner described moves the slide valve 21 to the position shown in Figure 6, whereupon steam will flow around the groove 22, and thence downwardly into the right hand cylinder 16 through the corresponding port 26. At the same time it will be apparent that communication between the upper end of the cylinder last referred to and the atmosphere will be cut off by the shifting of the valve 21, the groove 24 moving out of registration with the pipes 25 and 39. At the left side of the apparatus it will be noted that communication will be cut off between the groove 22 and port 26 upon the movement of the valve 21, and at the same time communication will be established between the upper end of the left hand cylinder and the atmosphere through port 39, groove 24 and exhaust pipe 25. Thus it will be apparent that steam pressure will be admitted into the right hand cylinder while the upper end of the other cylinder will be connected to the atmosphere.

Referring to Figure 1, it will be noted that both the cylinders 16 are mounted above the boiler, and when water is admitted to these cylinders it will be obvious that the level of this water will be above the level of the boiler water. When one of the cylinders 16 is exhausted to the atmosphere, the pressure of the water supplied by the pump 52 will unseat the corresponding check valve 47, thus permitting the water to flow into this cylinder and to lift the corresponding piston 27. As previously stated, the pistons 27 are of substantial weight, but the area of each is such that a substantially low water pressure is sufficient to elevate the pistons. Therefore the pressure of the water will elevate the piston causing it to move toward the top of the cylinder whereupon the valve shifting movement previously referred to will take place. At the same time the admission of steam into the other cylinder tends to equalize pressure on opposite sides of the piston, the lower end of the cylinder being in communication with

the boiler through pipes 11 and 18. As previously stated, the water in the last named cylinder will be above the level of that in the boiler and the water in the cylinder will tend to seek the level of the water in the boiler and this action will be greatly assisted by the weight of the piston. Thus it will be apparent that the pressure exerted will be sufficient to unseat the check valve 12 to permit the water to flow into the boiler. With the parts in the position shown in Figure 4, steam pressure is about to be admitted into the right hand cylinder whereby water will flow therefrom into the boiler while water will be admitted into the left hand cylinder. When the piston in the latter cylinder reaches the upper limit of its movement the bell crank lever 35 will be moved to shift the valve 31 to reverse the conditions whereby steam will be admitted into the left hand cylinder while the other cylinder will be connected to the atmosphere.

It will be obvious that the cylinders 16 are rigidly connected to each other only at their upper ends. As steam and water is alternately admitted into the cylinders, they will alternately expand and contract, and this expansion and contraction is permitted by virtue of the construction just referred to. The ball and socket connections between the pipes 44 and the lower cylinder heads permits the pipes 44 to rotate slightly about their axes as the lengths of the cylinders 16 are altered by expansion and contraction, and accordingly no damage will be done to the parts. The lengths and transverse connections of the water inlet and outlet pipes is such that the movement of the cylinders under the influence of expansion and contraction will be absorbed by the inherent flexibility of the pipes referred to. If, for any reason, the automatic operation of the apparatus stops, the valve 31 may be shifted manually through the axial extensions 37.

It is to be understood that the form of the invention herewith shown and described is to be taken as a preferred example of the same and that various changes in the shape, size and arrangement of parts may be resorted to without departing from the spirit of the invention or the scope of the subjoined claims.

I claim:

1. Apparatus of the character described comprising a pair of vertical cylinders adapted to communicate at their lower ends with the lower portion of a boiler, a piston mounted to reciprocate in each cylinder, a source of water sufficient to elevate said pistons, a pipe connected between said source and the lower ends of said cylinders, a check valve in said pipe adapted to open to permit water to flow into said cylinders, a valve cylinder, a valve reciprocable in said cylinder and movable to opposite ends thereof to

alternately connect said first named cylinders to the atmosphere and to the boiler to receive steam pressure therefrom, and means for shifting said valve comprising an auxiliary valve controlled by movement of said pistons and adapted to alternately deliver fluid pressure to opposite ends of said valve cylinder and to exhaust pressure therefrom.

2. Apparatus of the character described comprising a pair of vertical cylinders adapted to communicate at their lower ends with the lower portion of a boiler, a piston mounted to reciprocate in each cylinder, a source of water under pressure sufficient to elevate said pistons, a pipe connected between said source and the lower ends of said cylinders, a check valve in said pipe adapted to open to permit water to flow into said cylinders, a valve cylinder, a valve reciprocable in said cylinder and movable to opposite ends thereof to alternately connect said first named cylinders to the atmosphere and to the boiler to receive steam pressure therefrom, said valve cylinder being provided with a port communicating with each end thereof, and means for shifting said valve comprising an auxiliary valve adapted to alternately supply steam pressure from the boiler to said ports and to exhaust pressure therefrom, said auxiliary valve being controlled by movement of said pistons.

In testimony whereof I affix my signature.
ROBERT L. DENNISON.
